UNITED STATES PATENT OFFICE.

SIMON HEIDEN, OF DETROIT, MICHIGAN.

LOCOMOTIVE-TENDER-TANK FEEDER.

Application filed March 22, 1927. Serial No. 177,443.

The present invention relates to an improved locomotive tender tank feeder, that is, a means for filling the tender tank with water, and it has more particular reference to a structure which feeds the water while the train is in motion.

Briefly, the invention has reference to a structure of this kind, which embodies a suitably constructed and supported mono-rail, upon which a storage tank is mounted for movement, the storage tank including a control valve and operating means therefor which is controlled by novel co-acting means carried by the locomotive tender tank.

The arrangement is such that when the last named means engages the valve operating means on the reservoir or storage tank, the latter is carried along the rail to a predetermined point, after which it is automatically returned to a normal or starting position.

The particular features forming the alleged novelty will become apparent from the following description and drawings:

In the accompanying drawings:

Figure 1 is a side elevation showing the complete structure and the approximate manner of operation.

Figure 2 is a top plan view of the rail.

Figure 3 is a detail sectional and elevational view on an enlarged scale showing the internal construction of the reservoir more plainly.

Figure 4 is a view showing the valve operating means for the water supply pipe.

Figure 5 is a top plan view of said supply pipe and valve operating means.

In the drawings, the reference character 1 designates the suspension rail which comprises a single rail having an upwardly inclined portion 2 terminating in a somewhat elevated part 3. This rail is supported from right angular brackets 4 carried by the standards or posts 5. Obviously the posts and rails are arranged alongside of the track on which the tender tank 6 runs. The tank is provided with a filler neck 7 and a splash guard 8. Also on one end it is provided with a bumper bracket 9, and with a comparatively short valve actuating bracket 10. The cooperation of these parts will be brought out later.

The reservoir or travelling tank which contains the water is designated generally by the reference character 11. This is in the form of an open top rectangular box adapted to hold a predetermined quantity of water. Rising from the opposite end are supporting elements 12 for the grooved wheels 13, which

roll along the rail. At one end I find a pair of bumper springs 14 and 15, the spring 15 being adapted to engage the aforesaid brackets 9 and the springs 14 being adapted to engage a suitable stop 16, on the post 17 in Figure 3. This post, by the way, is located beyond the water supply pipe 18. This water supply pipe has a depending discharge neck at its upper end which is located over the travelling tank. Before considering the details of this pipe, I first wish to direct attention to the tank 11, which includes a discharge mouth 19 at its bottom adapted to align with the neck 7. This mouth is constructed to accommodate a closing valve 20, which is carried by a pivoted link 21, on the interior of the tank. This link 21 is operated from a bell crank 22 pivoted as at 23 on the exterior. One arm 24 of this crank is connected with a lifting pin, which is in turn connected with the intermediate portion of the link 21. The opposite curved arm 25 is adapted to cooperate with the aforesaid bracket 10.

Attention is now especially invited to Figure 4, wherein it will be seen that the discharge end of the water supply pipe 18 is provided with a constricted end portion having a valve seat 26, with which a plug valve 27 is engageable. This valve is on the end of the curved operating arm 28, having the extension 29. A suitable bracket 30 is provided for supporting the arm. Means is provided on the travelling tank 11 for operating this valve 27 through the medium of the parts 28 and 29. This means comprises a pair of cross bars 31, and 32, extending across the open top of the tank 11. These bars are provided with holes through which the stem 33 of the float 34 is mounted. As shown better in Figure 3, the upper end of this float stem 33 has an upwardly inclined operating finger 35, and a downwardly inclined finger 36, these being located in spaced relation to engage the extension 29.

It is yet to be pointed out, as shown in Figure 1, that I employ a pivoted return arm 37, and this arm has its opposite ends directed laterally inwardly from the supporting post, and a suitable spring 38 is provided for holding it in the approximate position shown. Incidentally there is another coil spring 39 mounted on the tank 11, and this is adapted for cooperation with this pivoted arm 37.

Attention is also invited to the presence of a resilient latch 40 which is fastened to one end of the tank. This is formed on its free

end with a beveled head which is adapted to engage an appropriate keeper 41 on the post 17. Obviously, these details are advantageous, for when the tank returns to its normal position, the latch snaps over the keeper and holds the tank here to prevent undesirable recoiling.

Incidentally, the upper end of the aforesaid bracket 9 is beveled for engagement with the head of the latch so that when the tender comes along, this bracket will engage the latch for lifting it and disengaging it from the keeper.

The operation is as follows:

15 Normally, the travelling tank or reservoir 11, is in the position shown in Figure 3, that is, in a position to the right of the water supply pipe 18. At this point I find the special post 17 which has a suitable stop 16 at its 20 top engaging the coiled bumper spring 14. Assuming that the tank is full of water and the tender tank comes along, it will be seen that the upstanding bracket 9 will first engage the latch 40 from the keeper 41 and will 25 then engage the shock absorbing spring 15, at about the same time the short bracket 10 will engage the depending arm 25 on the bell crank 22. In so doing the valve 20 will be opened so that the water will flow out of the 30 tank 11 into the tank 6. However, both of these tanks will move along at a slow rate, until the tank 11 approaches the pivoted arm 37. By this time, all of the water has been 35 emptied into the tender tank, the valve 20 having been held open during this period of travel. Then the spring 39 will engage the upper end of the arm 37 after the tank 11 has climbed up the incline 2 in the rail and assumed a position on the horizontal part 3 40 in the rail. This will allow the brackets 10 and 11 to clear the parts with which they were previously engaged and the tender will travel on and the tank 11 will remain in this position momentarily, when the spring 38 will 45 come into play to push the arm 37 back to the full line position in Figure 1, and then the tank 11 will be returned by gravity from the rail 1 to its normal position. At about the time that it reaches this position, the operating fingers 35 and 36 on the float stem 50 will come into play and will engage the ex-

tension 29 and the arm 30, in Figure 4, in succession. As the arm 35 engages the extension 29, a cam action will be produced, lifting the valve 27 and allowing water to flow out of the pipe 18 to refill the tank 11. At this time the valve 20 will, of course be closed. As the tank fills the float 34 rises and brings the finger 36 into play for producing a second cam action for closing the valve 27 and cutting off the supply. Then the apparatus is set for the next operation.

After carefully considering the description in connection with the drawings, a clear understanding of the construction and operation as well as the advantages will be had. Therefore, a more lengthy description is thought unnecessary.

Minor changes coming within the field of invention claimed may be resorted to if desired.

I claim:

1. In a structure of the class described, a suspension rail, a water supply pipe located alongside of the rail and having a control valve, operating means for said control valve including an extension, a storage tank supported from said rail and movable along the rail, a float in said tank, a stem carried by said float, and curved fingers extending at right angles from said stem and adapted for cooperation with the extension on the operating means for said valve.

2. In a structure of the class described, a suspension rail, a water supply pipe located alongside of the rail and having a control valve, operating means for said control valve including an extension, a storage tank supported from said rail and movable along the rail, a float in said tank, a stem carried by said float, curved fingers extending at right angles from said stem and adapted for cooperation with the extension on the operating means for said valve together with a discharge neck in the bottom of the tank, a valve cooperating with said neck, a link pivoted in the tank and connected to the valve, a pivoted bell crank on the exterior of the tank, and an operating connection between the bell crank and link.

In testimony whereof I affix my signature.

SIMON HEIDEN.
